UNITED STATES PATENT OFFICE.

ANDREW KLAY, OF BLUFFTON, OHIO.

CEMENT-BLOCK MACHINE.

No. 815,098.

Specification of Letters Patent.

Patented March 13, 1906.

Application filed August 28, 1905. Serial No. 276,138.

To all whom it may concern.

Be it known that I, ANDREW KLAY, a citizen of the United States, residing at Bluffton, in the county of Allen and State of Ohio, have invented a new and useful Cement - Block Machine, of which the following is a specification.

This invention relates to machines for the manufacture of building-blocks and the like from concrete or other plastic material, and has for one of its objects to provide a machine of simple construction which may be quickly and accurately adjusted for the manufacture of blocks of different dimensions.

A further object of the invention is to construct a machine in which the mold may be rapidly moved to open and closed positions and provide means for raising and lowering the removable pallet-board which forms the bottom of the mold during the molding operation.

A still further object of the invention is to provide a machine of this character in which the several side and end walls of the mold are formed of separately-detachable members which may be readily replaced by other members of different size or bearing different designs in accordance with the character of the block to be manufactured.

A still further object of the invention is to provide a machine having movable side and end walls in which a side wall and end wall are coupled together for mutual movement during the opening of the mold, provision being made, however, for moving said members in successive order at the starting of the operation in order to free said members from contact with the molded block.

A still further object of the invention is to provide a novel form of pallet supporting and operating mechanism whereby the pallet may be firmly locked in place during the molding operation and which will permit of the ready discharge of the pallet and block after the opening of the mold.

With these and other objects in view, as will more fully hereinafter appear, the invention consists in certain novel features of construction and arrangement of parts hereinafter fully described, illustrated in the accompanying drawings, and particularly pointed out in the appended claims, it being understood that various changes in the form, proportions, size, and minor details of the structure may be made without departing

from the spirit or sacrificing any of the advantages of the invention.

In the accompanying drawings, Figure 1 is a perspective view of a block-molding machine constructed in accordance with the invention. Fig. 2 is a vertical sectional view of the same on the line 2 2 of Fig. 4. Fig. 3 is a transverse sectional view of the same on the line 3 3 of Fig. 4. Fig. 4 is a sectional plan view of the machine on the line 4 4 of Fig. 2. Fig. 5 is a detail perspective view of one of the side members of the mold-box detached.

Similar numerals of reference are employed to indicate corresponding parts throughout the several figures of the drawings.

The various working parts of the machine are supported in a suitable frame, which in the present instance includes a bed or table 10, that is carried by standards 11.

The central portion of the table is open for the passage of the pallet-board-carrying devices, and near each corner of the table, which in the present instance is rectangular in form, is arranged a guide-block, these blocks 12, 13, 14, and 15 being securely bolted in position and the inner edge and inner end of each block serving as a guiding member for portions of the mold-box-carrying frame.

Extending lengthwise of the table and having their opposite ends resting on the upper surface thereof are two longitudinally-movable bars 16 and 17, the central portions of which are depressed and pass through the opening in the table, these central portions being provided with suitable strengthening-ribs 19. The bars are held in spaced relation by means of two plates 20 and 21, that are secured to opposite ends of the table, respectively, and one end of each plate is provided with a projecting rib 22, fitting in an undercut groove in the face of the guide-block, the rib of the bar 16 fitting in a groove in block 15, while the rib 22 of bar 17 fits within the groove of the block 12. Projecting from these two bars 16 and 17 are lugs 24 and 25, respectively, said lugs having openings provided with internal threads for the reception of the right and left hand threads of a screw 26, the outer unthreaded end of said screw extending through an opening in a bearing-bracket 28, that is carried by the plate 21. The screw is held from longitudinal movement by a collar 29 at one side of the bearing and by a hub 30 of a wheel 31 at the opposite side of said bearing. This wheel has a crank-

handle 32, which when turned in one direction or the other will cause movement of the two bars 16 and 17, the bars moving in opposite directions, respectively.

5 Secured to the upper face of the bar 16 is a bracket 33, carrying a horizontally-disposed guide-bar 34, the upper and lower edges of which are beveled, and this bar is adapted to receive and support one end member 35 of the mold. The rear face of the end member 35 has a dovetail guiding-groove for the reception of the guide-bar 34, and when necessary this member may be removed by sliding it lengthwise of the bar and another end 10 member substituted therefor, a number of interchangeable end members being employed in connection with each machine in order that blocks of different design may be made.

Secured to the bar 17 is a vertically-disposed bracket 38, having a guide-bar 39, arranged for the reception of a second end member 40 of the mold-box, this member being also provided with a dovetail groove for the reception of its guiding and supporting bar, 15 and in the present instance both end members are shown as provided with inwardly-projecting strips 41 at their lower edges, these being arranged to form a slightly-beveled face or corner around the bottom of the block. These strips may be removed and other strips of different size or shape substituted therefor in accordance with the character of the block to be made.

The inner ends of all of the guide-blocks 12 20 13, 14, and 15 are provided with undercut recesses for the reception of ribs 44, projecting from a pair of longitudinally-slidable bars 45 46, that are arranged transversely of the frame, the adjacent edges of the bars being in contact with each other and one being provided with a groove 47 for the reception of a rib 48, carried by the other. These two bars are provided, respectively, with inwardly-projecting lugs 50 and 51, having threaded 25 openings for the passage of a right and left hand screw 52, the outer end of which extends through an opening in a bearing-bracket 53, bolted to the frame. The screw is held from longitudinal movement in one direction by a collar 54 at the inner side of the bearing, and movement in the opposite direction is prevented by the hub of a wheel 55, that is provided with a suitable operating-crank 56. By turning this crank the screw 30 is revolved and the two bars are moved in the direction of their length, but in opposite directions, respectively. In order to prevent the entrance of any of the concrete or other material between the two bars 45 and 46, a pair of shield-plates 57 58 are employed, one plate being carried by one bar and the other plate by the opposite bar and the edges of the two plates overlapping to form a continuous guard.

65 To the bar 45 is secured a standard 60,

having a horizontally-disposed guide-bar 61, on which is slidably mounted one of the side wall members 62 of the mold, and the bar 46 is provided with a standard or bracket 64, having a guide-bar 65, on which is mounted 70 the second side wall member 66 of the mold-box. These side wall members are also shown as provided with the bottom strips 41, so that a continuous beveled face may be formed around the bottom of the block.

The two end members and two side members of the mold-box are shown in the present instance as comprising plates each having at its upper edge a horizontally-disposed flange 70, and this flange forms a convenient 80 guide for the troweling or similar member by which the surplus material is removed from the filled mold. These flanges are further provided with graduations, generally in inches and half-inches, in order to permit the 85 ready and accurate adjustment of the members for the formation of a block of any desired size, and for the purpose of more accurately adjusting said members the wheels 31 and 55 may be provided with graduations 90 indicating fractions of an inch. In practice the parts are so arranged that each complete revolution of one or other of the wheels will result in an adjustment of the mold members to the extent of one-half inch, while the periphery of each wheel is graduated for quarter, eighth, or other fractional parts of an inch, stationary pointers 71 being employed 95 to indicate the proper adjustment.

To the lower edge of each one of the mold members is secured a spring-strip 74, one end of the strip being rigidly bolted to the mold member, while the free end has an upturned lip 75 fitting under the edge of an adjacent mold member—that is to say, each side 100 member of the mold will be provided with a strip for engagement with one end member and each end member will be provided with a strip for engaging one side member. The distance between each lip 75 and the end wall 105 of the member which carries it is greater than the thickness of the wall of the member engaged, so that there is always some slight play between the two, this being necessary in order to free all of the members of the mold 110 by direct outward movement from the block, and after such members are once out of contact with the molded surface they may be moved in a direction parallel therewith in order to fully open the mold and permit the 115 discharge of the block. The spring-strips, moreover, are of such nature that by merely exerting downward pressure on any one of the lips 75 and then moving the member which carries the strip said member may be 120 detached from its carrying-bar and removed from the machine, permitting the substitution of another mold member having a molding-face of different character.

Pivoted to two of the legs or standards of 130

the frame is a lever 80, said lever being approximately U shape in general contour with its bifurcated end portions pivoted to the legs or standards, while the single arm extends between the two oppositely - disposed legs or standards and is provided with a downwardly-extending flange 82. This end of the lever is supported by a cam 83, that is rigidly secured to a transversely-extending shaft 84, adapted to suitable bearings in the standards, and said cam may be moved to either raise or lower the lever. The central portion of the lever is provided with an opening for the passage of a freely-movable stem 85, carrying at its upper end a bar or plate 86, from the ends of which project two sets of vertically-disposed pins 87 and 88, one pair of pins 87 extending through guiding-openings formed in the block 20, while the second pair extends through guiding-openings formed in a plate 89, that serves also as a shield for the screw 26. The upper ends of the pins are arranged for the reception of a removable pallet 90. These pallets may be formed of wood or metal, and in the latter case are generally plated or covered with a non-corrodible material in order to prevent injury to the block, and the lower surface of each plate is provided with recesses for the reception of the upper ends of the pins, so that the plate may be readily centered and held in proper position and form the bottom of the mold. In practice the pallet is held firmly against the lower edges of the side and end members by means of the cam 83 and lever 80 during the molding operation, and after the molding operation, during the movement of the mold members to open position, the pallet is elevated to a position above the flanges 70, so that it may be readily removed, together with the molded block.

The legs or standards which support the lever 80 are provided with bearing-openings for the reception of a transversely-extending shaft 92, having an operating-lever 93 at one end and provided at a point about midway of its length with a rocker-arm 94, that is arranged to engage the pin-carrying plate 86 for the purpose of elevating the pallet. The lever 93 is extended to a point below the shaft 92 and is provided with a pin 95, entering an elongated slot 96, formed in one end of a link 97. The opposite end of the link is connected to a rocker-arm 98 on the shaft 84 and serves as a means for transmitting movement to the cam 83.

In the operation of the device a pallet-board of proper size is placed on the pins 87 and 88, and lever 80 is lowered by turning the shaft 84 until the lever 80 rests on the smallest part of the cam 83. The pallet-board will then be some distance below the lower edges of the mold member, and the latter can be freely adjusted to form a mold-box of the required size.

The box is filled and tamped, and after the surface material has been troweled off the mold-box is opened. To effect the opening movement, one of the cranks 32 or 56 is slightly turned. If the crank 32 is turned, the two end members 35 and 40 will be moved away from each other and the molding-faces will be spaced from the molded block. The movement ceases when the lower ends of these members engage with the lips 75, projecting from the side members, for the reason that if further continued the side members would be moved in a direction parallel with the length of the molded block and as they assume contact with the block the molded surface of the latter would be mutilated. The crank 56 is then turned and the side members are separated, moving freely until their edges come into contact with the lips 75 of the spring-strips carried by the end members. This movement, however, is continued, and the end members are carried with the side members to open the mold, and no harm can result from this movement, inasmuch as the end members have already been spaced from the end walls of the molded block. If the pallet-board is of proper size, it may then be elevated through the mold; but if the board is larger than necessary the crank 32 is again turned in order to more widely space the end members 35 and 40. The operator then grasps lever 93 and moves the rocker-arm 94 into engagement with the plate 86, raising the latter, together with the pallet-board and molded block, the block being raised above the level of the flanges 70, so that it may be readily carried away.

A fresh pallet-board is then placed in position, and the operating-lever is moved in the reverse direction in order to lower the pallet-board to a position below the mold members. The latter are then readjusted by turning the cranks 32 and 56, after which the mold-box is in readiness for the reception of another mass of concrete or similar material.

With a device of this kind it is possible to quickly adjust the machine for the manufacture of blocks of any size, and as the end members and side members are all removable a block of any required design may be made.

Having thus described the invention, what is claimed is—

1. In a block-forming machine, a mold having side and end walls arranged in pairs, each pair constituting a side wall and an end wall, the walls of each pair being movable first singly and then simultaneously.
2. In a block-forming machine, a mold having movable side and end walls; means for loosely connecting the walls of the pairs, each pair constituting a side wall and an end wall, and a mold-opening means serving to space the walls from the molded block, and then to simultaneously move each pair of walls, one wall of each pair moving directly

away from the block, and the other in a direction in parallel relation therewith.

3. In a block-forming machine, a mold having movable side and end walls connected in pairs, each pair constituting a side wall and an end wall, and means for simultaneously moving all of the walls, the walls of each pair being loosely connected to permit independent movement at the starting of the mold-opening operation.

4. In a block-forming machine, a mold-box including movable side and end walls, an operating means connecting the two side walls for simultaneous movement, and means for connecting each side wall to an end wall to insure movement of the walls in pairs.

5. In a block-forming machine, a mold including movable side and end walls, means for connecting the end walls for simultaneous movement, means for connecting the side walls for simultaneous movement, and means for forming loose connections between each side wall and an end wall.

6. In a block-forming machine, a mold-box including movable side and end walls, a loose connection between one of the side walls and one of the end walls, an operating means for simultaneously moving said walls one in a direction away from the block, and the other parallel therewith, and means for spacing the latter wall from the molded block in advance of its movement with the first wall.

7. In a block-forming machine, a mold-box having movable side and end walls, guiding and supporting bars for said side and end walls, means for moving the guiding and supporting bars toward and from each other, and means for connecting the side and end walls in pairs, each constituting a side wall and an end wall, whereby movement of one set of guiding and supporting bars will space the walls carried thereby, and at the same time effect sliding movement of the remaining walls on their guiding and supporting bars.

8. In a block-forming machine, a mold-box including movable side and end walls, guiding and supporting bars for said walls, means for connecting said guiding and supporting bars and for moving the same toward and from each other, and loose connections between each side wall and an end wall, whereby movement of either with its guiding and supporting bar will effect sliding movement of the other on its guiding and supporting bar.

9. In a block-forming machine, a mold including side and end members, each movable in the direction of its length, and in a direction at a right angle to its length, and means for connecting such members in pairs, each pair constituting a side member and an end member.

10. In a block-forming machine, a mold-box including end walls and side walls, supporting and guide bars for said end walls and

side walls and on which said walls are movable in the direction of their lengths, and right-and-left end screws connecting said supporting and guiding bars in oppositely-arranged pairs.

11. In a block-forming machine, a mold-box including side and end walls, carriers on which said walls are movable in the direction of their lengths, a screw having right and left hand threads connecting the side-wall carriers, and a screw having right and left hand threads connecting the end-wall carriers.

12. In a block-forming machine, a mold-box comprising side and end walls, carrying members on which said walls are slidably mounted, a screw having right and left hand threads connecting the side-wall carriers, and a screw having right and left hand threads connecting the end-wall carriers.

13. In a block-forming machine, a mold-box including side and end walls having graduations for determining the size of the mold-box, carriers on which said side and end walls are slidably mounted, a screw having right and left hand threads connecting the side-wall carriers, a screw having right and left hand threads connecting the end-wall carriers, and loose connections for coupling the walls in pairs.

14. In a block-forming machine, the combination with side and end walls, of carriers on which said side and end walls are mounted, means for moving said carriers, and a spring carried by each wall and provided with an end tongue for engagement with the wall at a right angle thereto.

15. In a block-forming machine, a mold-box including side and end walls, each having a spring-strip projecting from one end thereof and having a terminal tongue or lip for engagement with the wall at a right angle thereto, wall-carriers on which said walls are slidably movable, and means for adjusting said carriers.

16. In a block-forming machine, the combination with a frame, of two pairs of slidable bars mounted thereon, one pair being at a right angle to the other, right and left hand screws connecting the bars of each pair, side and end walls having dovetail grooves, and guiding and supporting bars fitting within said grooves and mounted on the slidable bars.

17. In a block-forming machine, the combination with a frame, of the movable side and end walls, slidable bars arranged in pairs on said frame and carrying said walls, lugs projecting from the bars and provided with openings, screws having right and left hand threads fitting within said openings and serving as means for adjusting the bars, and guard-plates fitting over said bars.

18. In a block-forming machine, the combination with the side and end members of

the mold-box, of a removable pallet constituting the bottom of the mold-box, and means for forcing the pallet upward into engagement with the side and end members and locking the same in place during the molding operation.

19. In a block-forming machine, the combination with the movable side and end members, of a removable pallet forming the bottom of the mold-box, a plurality of pins on which said pallet is mounted, a supporting plate for said pins, a lever for elevating the plate, a cam for operating said lever, and an auxiliary means for engaging the plate and raising the pallet and molded block.

20. In a block-forming machine, the combination with the side and end members of a mold-box, of a removable pallet forming the bottom of the mold-box, a lever pivoted at

one end to the frame and disposed below the pallet, a cam engaging the free end of the lever, said lever having an approximately central opening, a stem guided in said opening, a plate secured to the stem, a plurality of pins extending from the plate and forming a support for the pallet, an operating-lever, a shaft on which said lever is secured, a rocker-arm on the shaft, said rocker-arm being arranged to engage the pin-carrying plate, and means operable through said lever for turning the cam.

In testimony that I claim the foregoing as my own I have hereto affixed my signature in the presence of two witnesses.

ANDREW KLAY.
